UNITED STATES PATENT OFFICE.

WALTER R. SCHLAGE, OF SAN FRANCISCO, CALIFORNIA, ASSIGNOR TO SCHLAGE LOCK CO., OF SAN FRANCISCO, CALIFORNIA, A CORPORATION OF CALIFORNIA.

DESIGN FOR AN ESCUTCHEON PLATE.

Application filed June 12, 1929. Serial No. 31,637. Term of patent 14 years.

To all whom it may concern:

Be it known that I, WALTER R. SCHLAGE, a citizen of the United States, residing at the city and county of San Francisco, State of California, have invented a new, original, and ornamental Design for Escutcheon Plate, of which the following is a specification, reference being had to the accompanying drawing, forming part thereof.

Figure 1 is a front view of the escutcheon plate,

Figure 2 is a central vertical longitudinal section.

I claim:

The ornamental design for an escutcheon plate, substantially as shown.

WALTER R. SCHLAGE.
